CLAIM

The ornamental design for a camera, as shown and described.

DESCRIPTION

FIG. 1 is a top, front and right side perspective view of a camera showing my new design;

FIG. 2 is a bottom, front and right side perspective view thereof;

FIG. 3 is a bottom, rear and left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of portion “10,” in FIG. 1;

FIG. 11 is a top, front and right side perspective view showing the camera in an alternative position; and,

FIG. 12 is a top, front and right side perspective view showing the camera in a used state.

The dashed-dot lines form the boundary of the enlarged portion view of FIG. 10 in FIGS. 1 and 10 and form no part of the claimed design. The even dashed broken lines shown in the drawings are included for the purpose of illustrating portions of the camera that form no part of the claimed design.
